(57) **CLAIM**

The ornamental design for a support leg, as shown and described.

DESCRIPTION

FIG. 1 is a perspective view of the new design for a support leg;

FIG. 2 is another perspective view thereof;

FIG. 3 is a front view thereof;

FIG. 4 is a back view thereof;

FIG. 5 is a bottom view;

FIG. 6 is a left side view; and,

FIG. 7 is a right side view.

The broken lines shown in FIGS. 1-7 illustrate portions of the support leg that form no part of the claimed design.

1 Claim, 7 Drawing Sheets

FIG. 1

FIG. 2

FIG. 3

FIG. 4

FIG. 5

FIG. 6

FIG. 7
